UNITED STATES PATENT OFFICE.

CORNELIOUS S. HOOVER, OF LANCASTER, PENNSYLVANIA.

DIAMOND MILLSTONE-DRESSING MACHINE.

SPECIFICATION forming part of Letters Patent No. 247,826, dated October 4, 1881.

Application filed March 25, 1881. (No model.)

To all whom it may concern:

Be it known that I, CORNELIOUS S. HOOVER, a citizen of the United States, residing at Lancaster, in the county of Lancaster and State of Pennsylvania, have invented certain new and useful Improvements in Diamond Millstone-Dressing Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention is an improvement on the machine described and shown in my patent dated October 7, 1879, and numbered 220,242. The object of said improvement is to provide convenient means for tilting one side or the other of the guide-frame, so as to adjust and hold the tool in an inclined position suitable for operating on the furrows of a left-hand dress or a right-hand dress, as desired. The devices employed to accomplish this object will be hereinafter more fully set forth and claimed.

20 In the accompanying drawings, Figure 1 represents a perspective view of a machine embodying my invention. Fig. 2 represents a detail view of the guide-frame for the carriage, with the locking-pins and adjusting-screws. Fig. 3 represents, in perspective, another form of my improved machine, in which the guide-frame has gudgeons (one at the middle of each end) instead of said pins; and Fig. 4 represents, in perspective, another form of my improved machine, in which the tilting is effected by means of screws which pass through straps or plates connected to a pair of wings and into the corners of the bed-plate or a permanent 25 attachment to the guide-frame. Fig. 5 represents an end view with the modifications shown in Fig. 4. Fig. 6 represents a detail view of the side locking-pin shown in Fig. 1, and proximate devices, the latter being partly in section.

30 A designates the bed-plate of my machine; B, the guide-flanges; C, the slide which rests upon and is guided by said flanges; D, the cross guide-bars on said slide; E, the diamond-carrier, which moves transversely to flanges

50 in said cross guide-bars; F, the handle set in the middle of this diamond-carrier, and receiving at its lower end the tool-stock of the diamond; G, a screw-tapped lug on said holder; H, an adjusting-screw, which works in said lug; K, a three-pronged cam, carried on the outer end 55 of the shaft of said screw; L, a handle for turning back said cam, and J a hanging arm carrying a pin, I, which is arranged to engage with said cam and rotate said screw when the slide reaches one end of the machine. The 60 construction, arrangement, and operation of the above parts are substantially the same as in my previous patent above mentioned. The machine described in said patent is, however, provided with no means for adjusting the tool 65 and diamond to an inclined position to the right or left for dressing furrows. My present improvement adds this adjustability and provides for locking the guide-frame in the position of adjustment thus taken. To accomplish this I employ any one of the several constructions hereinafter described. That which I prefer is shown in Figs. 1 and 2, which show the guide-flanges B B made separate from the bed-plate A and united by end bars or flanges, 70 b b, to form a rectangular guide-frame, B'. This guide-frame sets into a corresponding central recess of the bed-plate, which leaves room enough for the adjustment hereinafter described, and said guide-frame is supported by 75 detachable pins O O', which pass through end flanges of the base-plate, and into or through the end flanges, b b, of the guide-frame. These pins are four in number, one pair (designated O) being on the left side of the central longitudinal line of the machine, and the other pair (designated O') being on the right side of the 80 said line.

85 When all the pins are in place the frame B' is locked in a horizontal position. When, however, either pair of pins is removed the other pair serve as gudgeons or trunnions for the frame B' to turn upon, so that the other side can be tilted up, thus giving the entire frame an incline, and inclining also the slide, the 90 tool-carrier, the tool, and the diamond. This adjustment is effected by four screws arranged in the sides of the frame and working down

through the same against the inner part of bed-plate A, which is extended under the edge of said guide-frame, or into or against lugs formed on the inner edge of said plate. These screws 5 are arranged respectively near the four corners of said guide-frame, the two screws on the right being designated P and the two on the left being designated P'. By screwing one pair up and the other down the frame B' can be 10 tilted as desired, and they will hold said frame firmly in the inclined position thus given.

Sometimes, as shown in Fig. 3, I use a frame having two gudgeons, Q Q, permanently attached thereto and turning in bearings q q on 15 the bed-plate. In this case no removable pins are used as gudgeons, but the adjusting-screws are employed, as before. To still further secure the frame B' in its inclined position, a pin, R, is run in through a side flange of the bed- 20 plate and under a lug attached to said frame B'.

In Fig. 4 I have shown a form of my machine in which neither gudgeons nor detachable pins are used. The bed-plate A and the frame B' are rigidly attached together, and 25 they have a yielding connection with two wings, S S, by means of straps s s (four in number) and the four adjusting-screws. These screws pass through the curved and threaded inner ends of the straps and into suitably-threaded 30 recesses in the top of the bed-plate. The straps are permanently secured to the flat wings S S. By adjusting the screws up on one side and down on the other side, as before, the desired 35 inclination is given and retained. These screws have preferably a swivel-connection with the straps.

The improvement herein described, though 40 specially designed for use with the machine described in my previous patent, may also be applied to any other machine of the same general nature.

The pins hereinbefore described are preferably of tapering shape, and set into corre-

sponding recesses and perforations. Any other suitable form may be employed; but they should 45 be guarded against displacement.

I am aware that it is not broadly new to adjust the guide-frame of millstone-dressing machines so that it will tip laterally, nor to employ adjusting-screws for that purpose, nor to 50 provide such frames with removable pivots, and therefore I do not broadly claim such constructions or any of them; but,

Having thus described my invention, what I claim as new, and desire to secure by Letters Patent, is—

1. In a diamond millstone-dressing machine, the combination of a fixed frame or support with a pivoted guide-frame for the slide and holder and adjusting-screws passing down 60 through the sides of the movable frame and into the fixed frame, to provide for the pivoted adjustment of said guide-frame, so that either side thereof may be tilted.

2. The combination, with a bed-plate and 65 tilting guide-frame, of two pairs of removable pivot-pins inserted in the ends of the said tilting frame, one pair being on one side of the central line thereof and the other pair on the other side thereof, in order that the insertion 70 of all four pins may lock the frame in horizontal position and the removal of either pair will allow the other side of the frame to be adjusted upward or downward, substantially as and for the purpose set forth. 75

3. The combination of a side locking-pin, R, with a tilting guide-frame, the four adjusting-screws P, and a base-plate, substantially as set forth.

In testimony whereof I affix my signature in 80 presence of two witnesses.

CORNELIOUS S. HOOVER.
